UNITED STATES PATENT OFFICE

2,055,160

INDICATOR FOR CROSS-WORD PUZZLE GAMES

Herbert F. Scofield, New York, N. Y.

Application December 19, 1934, Serial No. 758,254

8 Claims. (Cl. 35—35)

My invention relates to improvements in game apparatus and the same has for its object to provide a simple, efficient, and inexpensive apparatus for ascertaining or determining the correctness of answers to words of a cross-word puzzle, or the correctness of any letter in a given word of a cross-word puzzle without disclosing the remainder of the answering words or of any of the remaining letters of such answering words.

Further, said invention has for its object to provide an apparatus adapted to receive a card bearing the complete solution to a cross-word puzzle, and by means of which it becomes possible to expose a single letter of any word appearing on said card without revealing any of the other letters of the same word or of any of the other words appearing on the "solution" card.

Further, said invention has for its object to provide an apparatus for use in connection with the solving of cross-word puzzles whereby, when the puzzles are being worked by two individuals or players in competition, and one of the players challenges the play of the other, the correct letter or word may be ascertained by reference to a solution card without disclosing or uncovering any of the other letters or words of the cross-word puzzle.

Further, said invention has for its object to provide an apparatus to be used in connection with cross-word puzzle apparatus as shown in my copending application filed December 19, 1934, Serial No. 758,253.

Other objects will in part be obvious and in part be pointed out hereinafter.

To the attainment of the aforesaid objects and ends my invention consists in the novel features of construction, and in the combination, connection and arrangement of parts hereinafter more fully described and then pointed out in the claims.

In the accompanying drawings—

Figure 1 is a face view showing one form of apparatus constructed according to and embodying my said invention;

Fig. 2 is a sectional view on the line 2—2 of Fig. 1;

Fig. 3 is a view similar to Fig. 1 with the cover or top plate of the apparatus partly broken away to show the interior construction;

Fig. 4 is a detail face view of the indicating device or marker;

Fig. 5 is an end view thereof;

Fig. 6 is a face view of a "solution" card;

Fig. 7 is a face view illustrating a modification;

Fig. 8 is a view similar to Fig. 7 with the top plate or cover partly broken away to show the interior construction, and

Fig. 9 is a detail face view of the indicating device or marker used in connection with the modified construction.

In said drawings 10 designates a relatively thin flat support of rectangular form preferably made of cardboard, wood or other suitable material and provided with a cover 10^a having a rectangular central opening 10^b. The support 10 is provided with a shallow recessed portion 11 whose edges terminate a short distance inwardly of the several edges of the support 10. The support 10 is further provided at its lower central portion with a vertical slot 12 which extends upwardly from its lower edge and terminates just above the center of the support. The entrance end of said slot 12 is provided with a cut-out portion 12^a.

Within the recess 11 is disposed a transversely or horizontally movable member 14 formed of cardboard or other suitable relatively thin material. The said member 14 is provided with a centrally-located vertical recess 15 within which works a slide 16 having its opposite vertical edges provided with recesses 17, and a relatively long, vertical base portion 18. The recesses 17 engage with and work upon the vertical edges of the vertical recess 15. The slide 16 is provided with a sight aperture 19 which corresponds in size and shape with one of the squares of the solution card 13. The said sight aperture 19 is normally concealed beneath a hinged cover 20. The slide 16 is further provided with horizontal indicating arrow 21, and gage marks 22 to indicate when the sight aperture 19 registers with any one of the "down" scale numerals on the movable member 14 which numerals correspond to the nine horizontal rows of squares on the solution card 13. A vertical arrow 23 and gage marks 24 are also provided upon the slide 16 to indicate when the sight aperture 19 registers with any one of the numerals of the "across" scale on the cover or top plate 11^a arranged adjacent to the lower edge of the recess 15.

The operation of the device is as follows:

When the operator desires, for example, to ascertain what letter appears in the fifth square of the fifth horizontal row of the solution card 13 he first moves the horizontally-movable member 14 to the right or left as the circumstances may require, until the arrow 23 and the gage marks 24 are brought into register with the numeral "5" of the "across" scale on the cover plate 11^a.

adjacent to the lower edge of the recess 15. He thereupon moves the slide 16 up or down, as the circumstances may require, until the arrow 21 and the gage marks 22 are brought into register 5 with the numeral "5" of the "down" scale on the movable member 14 adjacent the right hand edge of the recess 15, thereby bringing the sight aperture 19 in register with the fifth square of the fifth vertical row of the solution card. In the 10 operation just above described it happens that the fifth square of the fifth vertical row happens to be the fifth square of the fifth horizontal row, i. e., the two coincide. This is only true in a case where the square happens to be in the exact 15 center of the solution card, in other instances the squares will not coincide.

In the modification illustrated at Figs. 7, 8 and 9, 30 denotes a substantially flat support having a shallow central recess 31, and a vertical slot 32 arranged centrally of said support and extending from the lower edge thereof to a point near the center of the support. The said slot is designed to removably receive a solution card 33. Within the recess 31 is disposed a flat movable member 34 adapted for horizontal movement within the recess 31. The support is provided with a cover plate 30^a having a central rectangular recess 30^b. The movable member 34 is provided centrally with a vertical recess 35 having a 25 length equal to the number, in the present instance nine, of horizontal rows of squares, on the solution card 33, and a width equal to one of said squares, and at one side of said recess 35, and parallel therewith is secured a "down" scale 36 30 having nine divisions marked thereon numbered from "1" to "9", inclusive, and corresponding with the number of horizontal rows of squares on said solution card.

Upon the movable member 34 are secured in spaced relation a pair of guides 37, 37^a in which works a vertically-movable rack bar 38 having an arrow head pointer 39 at its upper end traveling over the "across" scale 40 provided with nine divisions numbered "1" to "9", inclusive, corresponding with the number of vertical columns of squares on said solution card 33. The pointer bar 38 is provided with a finger portion 41 for actuating the same, which finger portion also serves as a stop, and at one side between the guides 37, 37^a 45 said pointer bar is provided with a rack portion 42 adapted to engage with a tooth or stud 43 on a horizontally-movable slide 44 working in guides 45 secured to the vertically slidable member 46 working in said guides 37, 37^a. The slide 44 is 50 provided intermediate its ends with a sight opening 47 which corresponds in size and shape with one "square" of the solution card 33. The slide 44 is provided at one end with an arrow-head pointer 48 traveling over a "down" scale 36 carried on the movable member 34, and adjacent to its opposite end said slide is provided with a finger portion 50 for actuating said slide to interlock the tooth or stud 43 thereon with the appropriate 55 recess or notch in the rack portion 42. The finger portion 50 also serves as a stop to limit undue outward movement of said slide 44.

The operation of the foregoing construction is as follows:

A solution card 33 is first properly placed in 70 position within the slot 32 of support 30, and if it is desired to know, for example, what letter appears in the fourth square of the sixth vertical column of said card, it merely becomes necessary to move the horizontally slidable member 34 to the right or left, as circumstances may require 75

until the pointer 39 registers with the numeral "6" of the "across" scale, which number corresponds to the sixth vertical column of squares on the solution card. Hereupon the movable member 46 is shifted upwardly or downwardly, as the circumstances may require, until the pointer 48 5 registers with the numeral "4" of the "down" scale, which numeral corresponds to the fourth horizontal column of the solution card and then interlock the stud 43 with the appropriate notch 10 of the rack portion 42. When this has been done the letter will appear in the sight opening of the slide 47, and all the remaining squares of the solution card 33 will be concealed by the slidable member 46. 15

Having thus described my said invention, what I claim and desire to secure by Letters Patent is:

1. A device of the character described comprising a support adapted to receive a card having vertical and horizontal rows of characters or devices thereon, a horizontally movable member having an opening therein registering with the vertical columns on said card, indicating means associated with said horizontally-movable member for indicating the vertical columns of said card, a vertically movable member upon said first named member over the opening therein, said second named member having a sight opening therein registering with the opening in said horizontally movable member for exposing any portion of any of said vertical columns, and means associated with said vertically movable member for indicating the horizontal columns of said card and the particular character or device of any vertical column exposed to view through said last-named opening. 20

2. A device of the character described comprising a support adapted to receive a card having vertical and horizontal rows of characters or devices thereon, a horizontally movable member having an opening therein registering with the vertical columns on said card and coextensive in length therewith, means for said horizontally-movable member carried by said support for indicating the vertical columns of said card, a vertically-movable member carried by said first named member and disposed over the opening therein, said second named member normally concealing said card and having an opening therein registering with the opening in said horizontally-movable member for exposing any portion of any of said vertical columns, and means associated with said vertically-movable member for indicating the horizontal columns of said card and the particular character or device of any vertical column exposed to view through said last-named opening. 30

3. A device of the character described comprising a support having a card-receiving recess therein, a card disposed in said recess having vertical and horizontal rows of characters or devices thereon, a horizontally-movable member having a vertical opening therein registering with the vertical columns on said card and coextensive in length therewith, indicating means for said horizontally-movable member carried by said support including a scale having divisions thereon corresponding to the number of vertical columns on said card, a vertically-movable member carried by said horizontally-movable member having an opening therein registering with the opening in said horizontally-movable member for exposing any portion of any of said vertical columns, said members cooperating to conceal the remaining characters on said card, 35 40 45 50 55 60 65 70 75 80 85 90 95 100

and indicating means including a scale having divisions thereon corresponding to the number of horizontal rows on said card for indicating the particular character or device in any vertical column exposed to view through said last named opening.

4. A device of the character described comprising a support having a card-receiving recess therein, a card disposed in said recess having vertical and horizontal rows of characters or devices thereon, a horizontally-movable member having a vertical opening therein registering with the vertical columns on said card, means for guiding said horizontally-movable member on said support, indicating means for said horizontally-movable member carried by said support including a scale having divisions thereon corresponding to the number of vertical columns on said card, a vertically-movable member carried by said horizontally-movable member having an opening therein, a cover for said opening, said opening registering with the opening in said horizontally-movable member for exposing any portion of any of said vertical columns, means for guiding said vertically-movable member on said horizontally-movable member, indicating means including a scale having divisions thereon corresponding to the number of horizontal rows on said card for indicating the particular character or device of any vertical column exposed to view through said last named opening, and gage marks on said vertically-movable member registering with the divisions on said scales.

5. A device of the character described comprising a support having a card-receiving recess therein, a card disposed in said recess having vertical and horizontal rows of characters or devices thereon, a horizontally-movable member having a vertical opening therein registering with the vertical columns on said card, indicating means for said horizontally-movable member carried by said support including a scale having divisions thereon corresponding to the number of vertical columns on said card, vertical guides on said horizontally-movable member, a vertically-movable member working in said guides having an opening therein registering with the opening in said horizontally-movable member, horizontal guides between said vertical guides, a slide working in said horizontal guides having an opening therein for exposing any portion of any of said vertical columns, indicating means including a scale carried by said horizontally-movable member having divisions thereon corresponding to the number of horizontal rows on said card for indicating the particular character or device of any vertical column exposed to view through said last named opening, a rack member secured in said vertical guides, a pointer on said rack bar cooperating with the scale on said support, a stud on said slide engageable with said rack bar to hold said slide to adjusted position, and a pointer on said slide cooperating with the scale on said horizontally-movable member.

6. A device of the character described comprising a support having a card-receiving recess therein, a card disposed in said recess having vertical and horizontal columns of characters or de-

vices thereon, a horizontally-movable member having a vertical opening therein registering with the vertical columns on said card, indicating means for said horizontally-movable member carried by said support including a scale having divisions thereon corresponding to the number of vertical columns on said card, vertical guides on said horizontally-movable member, a vertically-movable member working in said guides having an opening therein registering with the opening in said horizontally-movable member, horizontal guides between said vertical guides, a slide working in said horizontal guides, means moving said slide, said slide having an opening therein for exposing any portion of any of said vertical columns, indicating means including a scale carried by said horizontally-movable member having divisions thereon corresponding to the number of horizontal columns on said card for indicating the particular character or device of any vertical column exposed to view through said last named opening, a rack member working in said vertical guides, means for adjusting said rack bar, a pointer cooperating with the scale on said support, a stud on said slide engageable with said rack bar to hold said slide to adjusted position, and a pointer on said slide cooperating with the scale on said horizontally-movable member.

7. A device of the character described comprising a support adapted to receive a card having characters or devices thereon arranged in intersecting rows, members disposed one above the other for movement transversely relative to each other and normally concealing the characters on said card, one of said members having an opening therein coextensive in length with the rows extending in one direction and the other member having a sight opening therein registering with the first mentioned opening and having an area limited to expose characters at intersections of the rows, and means associated with said members for indicating the rows in numerical order and the positions of said members relative thereto in order to expose through said sight opening the character at the intersection of the rows selected by adjustment of said members.

8. A device of the character described comprising a support adapted to receive a card having characters or devices thereon arranged in intersecting rows, members disposed one above the other for movement transversely relative to each other and normally concealing the characters on said card, one of said members having an opening therein coextensive in length with the rows extending in one direction and the other member having a sight opening therein registering with the first mentioned opening and having an area limited to expose characters at intersections of the rows, means for normally closing said sight opening, and means associated with said members for indicating the rows in numerical order and the positions of said members relative thereto in order to expose through said sight opening the character at the intersection of the rows selected by adjustment of said members.

HERBERT F. SCOFIELD.
